UNITED STATES PATENT OFFICE.

EUGÉNE FRANÇOIS SUTER, OF LONDON, ENGLAND.

APPARATUS FOR WAVING OR CURLING THE HAIR.

Application filed July 9, 1925, Serial No. 42,487, and in Great Britain June 18, 1925.

This invention relates to apparatus for waving or curling the hair by the method known as permanent waving.

Such apparatus comprises a number of electric heaters which are suspended from a position above that at which the treatment is to be carried out. Each of the heaters is suspended by a cord or other flexible member from a supporting frame, and the weight 10 of the heaters is balanced by passing each cord or flexible member over a guide pulley and suspending counter-weights from their opposite ends, so that thus the electric heaters may conveniently be brought down from 15 an elevated position into the position of use, and their weight balanced in that position, so that the weight of the heaters does not rest upon the head of the person undergoing the treatment, and the heaters are maintained 20 in their position in use without tension being applied to the hair in course of treatment.

In such apparatus the cords and counter-weights are liable to become entangled, and it is among the objects of the invention to 25 provide simple, convenient and effective means to avoid entanglement.

According to the invention the counter-weights are adapted to be guided in parallel 30 guide-ways advantageously provided within a parallel series of juxtaposed tubes, conveniently connected together whereby the heaters are adapted always to be freely used without liability of entanglement or derangement of the cords and counter-weights.

35 The invention comprises the construction hereinafter described.

The invention is illustrated by way of example in the accompanying drawings in which

40 Figure 1 is a plan view of an apparatus constructed according to the present invention.

Figures 2 and 3 are corresponding side and 45 rear elevations in which the length of the supporting pillar is interrupted, while

Figure 4 indicates in side elevation the same apparatus in its full height, and

Figure 5 is a detail plan view on the line 5—5 Figure 2.

50 Figure 6 is a detail sectional view of the clamping wheel.

In carrying the invention into effect in its application to the portable apparatus illustrated in the accompanying drawings, I provide a stand comprising a vertically disposed 55 supporting stand or pillar *a* conveniently

made of metal tubing, and a base socket fitting *b* having advantageously a number of radially disposed feet *b*¹ supported at or near their ends on casters, within which socket or base fitting, the lower end of the supporting stand or pillar is mounted; and I provide means by which the supporting pillar may be vertically adjusted to any desired height and secured in its adjusted position. Such means may advantageously 60 consist of a stud *c* (Figure 6) secured to the supporting stand or pillar *a* near its lower end, and adapted to extend outwardly through an axial slot *b*² in the socket fitting *b*, a clamping wheel *d* being mounted on the outer end of the stud *c* by means of which the supporting stand or pillar *a* may be tightly clamped in its adjusted position in 65 the socket fitting *b* and released when it is desired to change the height of the supporting pillar.

The upper end of the supporting stand or pillar *a* is conveniently provided with a transversely extending arm *a*¹ adapted to carry 80 at its upper end a supporting member or frame *e*. This supporting member or frame *e* may be formed of two concentric rings *e*¹, *e*² connected together by radially disposed parts *e*³ and in a central position to a boss *e*⁴ by which the supporting member or frame *e* is carried at the end of the arm *a*¹. Beneath and upon the respective rings *e*¹, *e*² a set of pulleys *f* are mounted advantageously 85 within pivoting brackets, and these pulleys 90 serve to determine the position at which the heaters *g* depend from the supporting member or frame *e*. The flexible members or cords *h* by which the heaters *g* are respectively carried pass over such pulleys *f*, and thence over a set of guide pulleys *i* disposed 95 in series in an adjacent position at or about the level of the supporting frame *e* whereby the ends of the flexible members or cords are brought into adjacent positions. Thus by 100 reason of the separation of the pulleys *i* from the pulleys *f* the respective ends of the flexible members or cords are separated. The guide pulleys *i* may conveniently be mounted upon a support or fitting *j* secured to the 105 supporting stand or pillar *a* near its upper end, which support or fitting *j* comprises two arms respectively extending on each side of the stand or pillar *a* and which arms are each slightly inclined rearwardly, and one half 110 the number of guide pulleys *i* are mounted to depend from one arm and one half from

the other, and the cords or flexible members *h* pass over the respective guide pulleys *i* and thence vertically downward. At their lower ends the cords or flexible members *h* have counter-weights *k* connected, and these respective counter-weights are adapted to slide within a corresponding series of vertical juxtaposed guideways or tubes *l*. The series of guideways or tubes *l* may be carried at their respective ends in transversely disposed frame members or fittings *m*, *m* which are mounted upon the socket fitting *b*, so that thus the fittings *m*, *m* and the guideways or tubes *l* form an integral part. The respective guideways or tubes *l* may be disposed substantially in alignment with the guide pulleys *i*, and thus the respective guideways or tubes *l* may be mounted in two sets, one at each side of the socket fitting *b*; and the respective end fittings *m*, *m* by means of which the guideways or tubes *l* are connected at their respective ends, are disposed at an angle corresponding to the position of the respective arms *j*, on which the guide pulleys *i* are carried at the upper end of the supporting pillar.

It will be understood that the leads *n* may be connected to a plug-box *o* centrally disposed beneath the supporting frame *e*, and also carried from the arm *a*¹ referred to; and that one or other number of heaters *g* may be connected and suspended together from the same cord or flexible member *h*.

It will also be understood that the invention is not limited to the construction of the guideways, as these may be formed in any desired manner without departing from the invention; thus, for example, the guideways may be formed by the juxtaposition of two corrugated metal sheets by which a series of parallel guideways are formed, and the manner of the support of the guideways upon the supporting pillar may be varied according to particular requirements.

It will be understood that the invention is also of application to apparatus of a similar kind that are permanently erected, and in the application to such apparatus it will be understood that the supporting pillar may be dispensed with and the guideways provided and supported in any convenient manner.

I claim:—

1. Apparatus for waving or curling the hair, comprising a stand adapted to support the whole of the said apparatus from the ground, a supporting member at the upper part of the said stand, the said supporting member extending outward laterally to overhang from the said stand and adapted for the support of a number of separate movable flexible members, the said separate movable flexible members suspended from the said supporting members, electrical heaters respectively depending from one end of the said

movable flexible members beneath the said supporting member, means upon the said stand for the support of the said movable flexible members in position adjacent the said stand at their ends opposite to those from which the said electric heaters respectively depend and are supported in position adjacent to each other and away from the said supporting member, counterweights respectively carried at the said adjacent ends of the said flexible members, and juxtaposed and substantially vertically disposed guideways upon and in position adjacent the said stand, within which guideways the said counterweights respectively slide on the raising or lowering of the respective heaters, substantially as described.

2. Apparatus for waving or curling the hair, comprising a stand adapted to support the whole of the said apparatus from the ground, a supporting frame mounted at the upper part of the said stand, the said supporting member extending outward to overhang from the said stand and the said supporting frame being substantially horizontally disposed, a number of guide pulleys carried by the said supporting frame, a support (such as *j*) on said stand laterally disposed with reference to the said supporting frame, guide pulleys carried upon the said support in juxtaposed positions adjacent the said stand and corresponding in number to the guide pulleys carried by the said supporting frame, movable flexible members each passing over one of the pulleys carried by the said supporting frame and over one of the pulleys carried on the said support respectively, heaters respectively carried at one end of the said movable flexible members in position beneath the said supporting frame, counterweights respectively carried at the other end of the said movable flexible members in position beneath and in line with the respective guide pulleys carried by the said support, and juxtaposed guideways within which the said counterweights slide on the raising or lowering of the corresponding heaters, said guideways being disposed in position adjacent the said stand substantially as described.

3. Apparatus for waving or curling the hair, comprising a stand adapted to support the whole of the said apparatus from the ground, a series of guideways provided as juxtaposed substantially vertical tubes carried by the said stand, counterweights adapted to slide within the said guideways, movable flexible members to the ends of which the said counterweights are respectively connected, a set of pulleys disposed in position immediately above the said respective guideways and carried on the said stand, a supporting frame extending outwardly to overhang from and be supported by the said stand, a second set of pulleys car-

ried upon the said supporting frame, the said movable flexible members passing over one pulley of each of the said sets, and electrical heaters respectively connected to said supporting frame, substantially as described.

4. Apparatus for waving or curling the hair, comprising a stand, a base socket fitting and a supporting pillar, the lower end of which is mounted within the said base socket fitting and the upper end of which is extended outwardly, a supporting frame carried by the outwardly extending part of the said supporting pillar, the said supporting frame being substantially horizontally disposed, a series of substantially vertical juxtaposed guideways carried by and at each

side of the base socket fitting, counterweights adapted to slide within the said guideways, means for the support of a set of pulleys upon the said supporting pillar, the said respective pulleys being disposed above and in line with the said respective guideways, a second set of pulleys carried upon the said supporting frame, movable flexible members respectively supported upon one pulley of each of the said sets carrying at one end one of the said counterweights, and electric heaters respectively carried at the other end of the said respective movable flexible members, substantially as described.

EUGÉNE FRANÇOIS SUTER.
